RAILWAY BRAKE

Carl E. Tack, Chicago, Ill., assignor to American Steel Foundries, Chicago, Ill., a corporation of New Jersey

Application October 7, 1954, Serial No. 460,824

5-Claims. (Cl. 188—207)

The invention relates to a railway brake arrangement and particularly to a novel brake beam assembly and brake beam supporting arrangement.

The invention comprehends utilizing a brake beam arrangement having friction means at the opposite ends thereof engageable with the wheel threads of an associated wheel and axle assembly upon movement of the beam.

Particularly, the invention contemplates an arrangement whereby a plurality of hangers pivotally carry the brake beam from the frame, said plurality of hangers being located at the opposite ends of the beam. Additionally, the invention comprehends a novel adapter casting readily associated with a brake beam of the unit type whereby the unit type beam may be converted to the hanger type beam and thus be pivotally carried from the associated truck frame. The invention has particular utility where space limitations or the addition of other types of equipment to the railway car truck prevent the utilization of the conventional slot supporting arrangement for the unit type beam.

Accordingly, it is a primary object of the invention to provide a unit type beam with an arrangement whereby it may be pivotally hung from the frame of an associated truck frame.

It is an additional object of the invention to provide an adapter casting which will readily facilitate the conversion of the unit type beam to a hanger type beam.

It is another additional object of the invention to provide an adapter casting which accommodates a plurality of pivotal supports from the beam at each end of the beam thereby eliminating the necessity for a fourth point support heretofore utilized in the art.

These and other objects of the invention will become apparent from the course of the following description and from an examination of the drawings, wherein:

Figure 1 is a fragmentary top plan view of a portion of the railway car truck embodying the invention,

Figure 2 is a fragmentary side elevational view of the structure shown in Figure 1,

Figure 2A is a fragmentary view taken along line 2A—2A of Figure 2,

Figures 3, 4 and 5 are respectively side elevational top plan, and end elevational detail views of the novel adapter casting employed in the invention, and

Figure 6 is a sectional view taken along lines 6—6 of Figure 1.

It should be noted that in the various figures, certain structural details have been omitted where it is believed said details are more clearly shown in one of the other figures.

Describing the invention in detail and directing attention to Figure 1, it will be seen that a railway car truck comprises a wheel and axle assembly 2, said assembly supporting a frame 4 in the usual manner (not shown), as is well understood by those skilled in the art. A brake beam 6 is positioned on one side of the assembly

2

2 and generally parallels the axis of the assembly, said beam 6 being of the truss type having compression and tension members 8 and 10, respectively, said members being joined centrally thereof by a strut 12, which has 5 a central slot 14 which receives and pivotally connects to a brake lever 16. The brake lever 16 is operatively connected via pull rods 18 and 20 to brake linkage (not shown) whereby the beam 6 may be moved in wheel engaging position as is well understood by those skilled 10 in the art.

The brake beam 6 is provided with brake head-brake shoe assemblies 12 adjacent the ends of the beam, said assemblies being arranged to engage the tread of the associated wheel. A flat guide lug 15 is formed on the 15 end of the beam outboardly of the brake head assembly 12. Thus it will be seen that the beam employed in the invention is that type conventionally known in the art as the unit type beam, said unit type beam normally being received within a slot defining bracket formed on 20 the frame and normally guided linearly by the slot into engagement with the related wheel tread of the associated assembly.

Frame 4 is provided adjacent its end with a pair of integrally formed brackets or jaws 19 and 21, respectively, 25 the bracket 21 pivotally receives the upper end of a main hanger 23, said hanger being preferably of a rectangular loop formation as is shown in fragmentary Figure 2A. An auxiliary or balance hanger 22 is received within the jaw 19, said hanger 22 also being preferably of rectangular loop formation.

Directing attention to Figure 6, it will be seen that the brackets 19 and 21 are each provided with aligned slots 25, 25, said aligned slots 25 received locking pin assemblies 26, whereby the upper ends of the hangers 35 22 and 24 are positively held in position within the respective brackets.

Directing attention to Figures 3 through 5, it will be seen that the novel adapter casting is indicated generally at 28 and comprises a base portion 30, said base portion 40 having up-raised arcuate lugs 32, 32 at opposite ends thereof, said lugs defining arcuate pivots 34, 34 and communicating slots 36, 36. A pair of spaced arms 38, 38 depending from the lower side of the lower portion of the base portion 30, said arms having fingers 40, 40 45 formed on the lower end thereof, said fingers being bent to a normal position relative to the associated arms 38. It will thus be seen that the arms 38 and fingers 40 define a slot 42 of general rectangular contour, said slot extending transversely of the adapter casting 28.

Directing attention to Figure 2, it will be seen that the slot 42 of the adapter casting 28 receives the lug 15 on the associated end of the beam 6. The casting 28 may be fixedly and demountably secured to the beam in any suitable manner, as for example by welding as at 44. 55 The pivots 34, 34 on opposite ends of the casting 28, respectively, receive the lower ends of the hangers 23 and 22. Locking pins 46, 46 serve to maintain the hangers 23 and 22 in pivotal association with the pivots 34 of the casting 28.

Thus it will be seen that I have provided a novel hanger type beam arrangement and a novel adapter casting whereby a unit type beam may be converted to a hanger type beam.

I claim:

65 1. In a brake arrangement for a railway car truck, a wheel and axle assembly, a frame supported thereby, a brake beam adjacent the assembly, a brake shoe assembly on the beam engageable with the wheel, a flat lug on the end of the beam, an adapter casting fixed to the lug, a 70 pair of spaced pivot points on the casting, and a pair of parallel hangers having their respective lower ends

pivots secured to the pivot means and their respective upper ends pivots secured to the frame, said beam being movable in an arc whereby the transverse plane of the beam is always at the same angle with respect to the horizontal to insure full face engagement between the brake shoe assembly and the wheel and axle assembly.

2. In a brake arrangement for a railway car truck, a wheel and axle assembly, a frame supported thereby, a brake beam disposed next to the assembly and having friction means thereon engageable with the wheels, a casting removably secured to the beam, pivot means on the casting, and parallel hanger means pivotally connected to the pivot means and pivotally connected to the frame, whereby the beam is movable in an arc with its transverse plane always maintaining the same angle with respect to the horizontal.

3. In an adapter casting to convert a unit type brake beam to a hanger type brake beam, a base, arcuate pivot means, a pair of arms extending from the base and having the ends thereof bent to face each other.

4. In an adapter casting to convert a unit type brake beam to a hanger type brake beam, a base, means to secure the base to the lug of a unit type beam, said

means comprising a pair of spaced arms extending from the base and fingers on the base angularly arranged relative to the arms, and pivot means on the base adapted to operatively receive hanger means.

5. In a brake arrangement for a railway car truck, a wheel and axle assembly, a frame supported thereby, a truss type brake beam disposed next to the assembly, said beam having tension and compression members and having end portions outboardly of said members, friction means on the end portions engageable with the wheels, respectively, hanger mounting means on the end portions of the brake beam, said hanger mounting means being operative to pivotally connect each end portion to a pair of brake hangers spaced longitudinally of the truck, whereby the beam is pivotally connected to the frame and movable in an arc whereby the center plane of the beam is always maintained in a constant angle with respect to the horizontal.
